Primary Examiner — Philip S Hyder

(57) **CLAIM**

The ornamental design for a mason's trowel, as shown and described.

DESCRIPTION

1. Mason's trowel

FIG. 1.1 is a perspective view.

FIG. 1.2 is a top plan view.

FIG. 1.3 is a front elevation view.

FIG. 1.4 is a rear elevation view.

FIG. 1.5 is a bottom plan view.

FIG. 1.6 is a side elevation view.

FIG. 1.7 is a side elevation view.

The broken lines in FIG. 1 illustrate aspects of the mason's trowel that form no part of the claimed design.

1 Claim, 7 Drawing Sheets
